INSERT FOR CONCRETE CONSTRUCTIONS

Frank D. Reiland, Chicago, Ill.

Application August 13, 1938, Serial No. 224,693

5 Claims. (Cl. 72—105)

This invention relates to certain new and useful improvements in inserts for use in concrete constructions to serve as anchorages for bolts or similar holding means which support other devices or constructions from the concrete beams.

An insert of this type is usually metallic and is formed with an internal pocket to receive a nut or the head of a bolt, there being a restricted opening leading through the face of the insert 10 through which the shank of the bolt passes. The insert is first nailed or otherwise temporarily secured to the inner face of a portion of the wooden mold or form in which the concrete is poured, with the open face of the recess against 15 the wood. After the concrete has set and the wooden form or mold has been removed, the insert will be embedded and anchored within the concrete, with its outer open face substantially flush with the outer wall of the concrete 20 member so that the bolt may be attached. Such inserts are used, for example, in ceilings or overhead beams to support hangers for pipes or other devices, or may be used in vertical walls or beams to support hangers or anchorages for the outer 25 brickwork or sheathing of a building. The insert may be in the form of a unitary casting (as in the forms hereinafter described by way of example), or may be built up of sheet metal. The invention hereinafter set forth is applicable 30 to any of these forms of inserts.

Although the open face of the insert is theoretically sealed by the form to which it is secured during the concrete pouring operation, it often happens that due to inequalities or unevenness 35 in the meeting faces of the insert and wooden form, or to the fact that the insert is not tightly secured against the form, cracks will remain through which liquid material may seep into the opening or pocket in the insert. Also, as the concrete is poured into the form it is usually stirred 40 by mechanical agitators and this often has the effect of loosening the nails by which the insert is temporarily secured to the form and causing gaps through which the wet concrete or grout 45 may be forced into the insert. The grout or wet concrete which finds its way into the opening and pocket in the insert will more or less fill and clog these openings and is very difficult to remove, particularly from the internal pocket 50 which is of much greater area than the restricted opening through which the bolt-shank projects. Many different methods have heretofore been proposed for preventing this clogging of the openings in this type of insert, or of open channel members which are similarly embedded in

concrete constructions. The more common method is to fill the channel or pocket with some readily removable material such as paper or felt which may be withdrawn after the concrete pouring operation is completed. This method is not well adapted for inserts of the type herein discussed, since it is difficult to remove this material through the small or restricted opening leading into the much larger internal pocket. Different forms of plugs for the opening have also 10 been proposed.

According to the improvements of the present invention, a gasket or closure of felt or similar compressible material is temporarily glued to the outer face of the insert around and over the opening. Preferably a shallow recess is formed in the outer face of the insert into which the strip of compressible material is fitted and temporarily secured. When the insert is nailed to the wooden form, this closure or compressible material will be compressed between the insert and wooden form so as to form an effective seal which positively prevents the entrance of any liquid or concrete into the insert. After the concrete has set and the wooden form has been removed, this felt strip can be easily torn away, leaving the opening and pocket clean and dry. It is also desirable to keep the interior of the insert clean and dry during the handling and shipping prior to the actual installation, and these improved 20 closures are preferably applied at the factory and not removed until the concrete construction process has been completed.

The principal object of this invention is to provide an improved insert of the type briefly described hereinabove and disclosed more in detail in the specifications which follow.

Another object is to provide an improved method of sealing inserts as used in concrete building construction.

Other objects and advantages of this invention will be more apparent from the following detailed description of certain forms of the invention constructed and operating according to the principles of this invention.

In the accompanying drawing:

Fig. 1 is a perspective view of one of the complete assemblies as furnished by the factory.

Fig. 2 is a view similar to Fig. 1, with the temporary closure member removed.

Fig. 3 is a vertical section through the assembly, taken substantially on the line 3—3 of Fig. 1.

Fig. 4 is a horizontal section through the insert as applied to the inner face of the wooden mold or form.

Fig. 5 is a section similar to Fig. 4 showing the insert after the concrete has been poured, the temporary closure removed, and the holding bolt installed.

5 Fig. 6 is a front elevation of a modified form of insert, showing the yieldable closure partially removed.

In the examples here shown the insert is in the form of a unitary casting, preferably of malleable 10 rust-resistant metal. The main body portion 1 of the insert is of hollow boxlike form enclosing an inner pocket 2. This housing is entirely closed at its sides, ends and back, and is partially closed at the front by the web or front 15 wall 3 provided with the central elongated opening 4 of sufficient width to permit the shank of the bolt or other holding means to pass therethrough. In the form shown in Figs. 1 to 5, a nut 5 (see Fig. 5) may be inserted through the opening by tipping the nut sidewise, and when this 20 nut is straightened into position it may be engaged by the threaded shank 6 of a bolt 7. In the alternative form shown in Fig. 6, one end of slot or opening 4 is enlarged as indicated at 8 25 so as to permit the head of the bolt to be inserted into the pocket, the nut being applied to the threaded outer end of the bolt. Obviously this bolt can be used for holding or suspending any desired device or construction.

30 The member indicated generally at 9, and projecting from the rear of the main body 1, serves to anchor the insert within the concrete, and the projecting rear flanges 10 and 11 serve as additional anchorages. Laterally projecting 35 ears 12, preferably aligned with the front face 13 of the insert, are provided with holes or open slots 14 for receiving the nails or screws 15 by which the insert is temporarily attached to the inner surface of the wooden form 16, as indicated 40 in Fig. 4.

45 Preferably a shallow recess 17 is formed in the front face of the insert about the slot or opening 4. This recess will be of sufficient area to provide a considerable bottom surface around opening 4, and this recess will most conveniently be of rectangular contour. The temporary closure or gasket 18 is preferably in the form of a sheet or strip of tough but yieldable or compressible liquid-resistant material, for example 50 jute-felt. This closure is preferably of substantially the same outer contour as recess 17 so as to fit snugly therein, and will be of substantially greater thickness than the depth of the recess so as to normally project forwardly from the front 55 face 13 of the recess as indicated at 19 in Figs. 1 and 3. Any convenient means may be used for temporarily holding this compressible closure within recess 17, but preferably the closure is secured in place by a suitable glue, and the bottom 60 surface of recess 17 is preferably roughened as indicated at 20 in Figs. 2 and 3 to provide a surface to which the glue will adhere. The ordinary rough unmachined surface of a casting will ordinarily be adequate for this purpose.

65 The felt closure 18 is preferably applied at the factory, and will remain in place until the concrete construction has been completed and the installation of bolt 7 is required. In this way the interior pocket 2 and opening 4 will be kept 70 clean and dry during any handling and shipping operations.

75 When the insert is installed in the molding form, as indicated in Fig. 4, the closure or gasket will be tightly compressed between the insert and the inner surface of the wooden form so as to

form an effective seal or gasket between the two members. For this reason many of the advantages of this invention would be obtained if the closure, instead of being in the form of a continuous sheet or strip so as to cover the slot 4, 5 were in the form of a ring or gasket positioned in recess 17 around or about the opening. However, it is preferable to have the closure 18 in the form of a continuous sheet or strip so as to close the slot 4 at all times. It will be noted that the 10 front faces of the ears 12 are preferably positioned in the same plane as the front face 13 of the insert so as to prevent any possible tipping of the insert as might occur if these ears were positioned further to the rear and one nail were 15 driven in further than the other. It will be noted in Fig. 4 that the ears 12 are secured substantially flush with the inner surface of the wooden form 16, the closure 18 being compressed almost completely within recess 17. 20

After the concrete 21 (see Fig. 5) has been poured and has set, and the wooden forms have been removed, the closure 18 will again be exposed and can easily be ripped out and discarded as soon as access to the interior of the insert 25 is necessary for installing the nut or bolt. The temporary closure is shown in partially withdrawn position in Fig. 6. This felt closure can be easily ripped out by inserting a suitable tool beneath one edge of the closure, or a hole could 30 be punched into the central portion of the felt member which overlies the opening 4 and then the felt member can be pulled away.

It will be apparent that the metallic frame 35 formed around the closure 18 by the sides and end walls of recess 17 serves to protect and enclose the edge portions of the felt closure. This serves to prevent or minimize the chances of the closure being accidentally broken loose or torn away during the handling, shipping and installation processes. 40

It will be understood that these inserts may be made of various sizes or forms, and may be built up of sheet metal or other material instead of constructed as unitary castings as in the examples hereinabove described. In any case, the compressible closure member may be applied in substantially the same manner as hereinabove described. 45

I claim:

1. A metallic insert adapted to be embedded in a concrete construction with its outer face exposed, said insert serving as an anchorage and formed with an internal pocket and a restricted opening leading from the pocket through the outer face of the insert, and a closure member of readily compressible sealing material temporarily secured to and projecting outwardly from the outer face of the insert to cover the opening. 50

2. A metallic insert adapted to be embedded in a concrete construction with its outer face exposed, said insert serving as an anchorage and formed with an internal pocket and a restricted opening leading from the pocket through the outer face of the insert, and a strip of compressible felt material glued to and projecting outwardly from the outer face of the insert around the opening. 65

3. A metallic insert adapted to be embedded in a concrete construction with its outer face exposed, said insert serving as an anchorage and formed with an internal pocket and a restricted opening leading from the pocket through the outer face of the insert, and a strip of com- 70 75

pressible felt material glued to and projecting outwardly from the outer face of the insert to cover said opening.

4. A metallic insert adapted to be embedded in a concrete construction with its outer face exposed, said insert serving as an anchorage and formed with an internal pocket and a restricted opening leading from the pocket through the outer face of the insert, the outer face of the insert being formed with a shallow recess of greater area than the opening, a strip of readily yieldable sealing material of substantially the same area and contour as the recess and of greater thickness than the recess, and means

for temporarily securing the strip within the recess.

5. A metallic insert adapted to be embedded in a concrete construction with its outer face exposed, said insert serving as an anchorage and formed with an internal pocket and a restricted opening leading from the pocket through the outer face of the insert, the outer face of the insert being formed with a shallow recess of greater area than the opening, and a strip of felt of substantially the same area and contour as the recess and of greater thickness than the recess glued within said recess. 5
